UNITED STATES PATENT OFFICE.

JAMES A. HERRICK, OF PHILADELPHIA, PENNSYLVANIA.

FURNACE.

No. 802,102.

Specification of Letters Patent.

Patented Oct. 17, 1905.

Application filed January 9, 1904. Serial No. 188,300.

To all whom it may concern:

Be it known that I, JAMES A. HERRICK, a citizen of the United States, residing at Philadelphia, in the county of Philadelphia and State 5 of Pennsylvania, have invented certain Improvements in Furnaces, of which the following is a specification.

This invention relates more particularly to furnaces of the regenerative type; and it has to as its primary objects to provide an improved construction having means for taking care of the slag that overflows at the ports, to provide an improved arrangement of the regenerative apparatus, and to compact and 15 strengthen the structure.

The nature and characteristic features of the improvements will more fully appear by reference to the following description and the accompanying drawings in illustration there- 20 of, of which—

Figure 1 represents a front elevation, partially in section, of a furnace embodying the improvements. Fig. 2 represents a vertical sectional view taken on the line 2 2 of Fig. 1. 25 Fig. 3 represents a vertical sectional view taken on the line 3 3 of Fig. 1, and Fig. 4 represents a horizontal section taken on the line 4 4 of Fig. 1.

As shown in the drawings, the heating- 30 chamber 1 has the superposed ports 2 and 3 communicating therewith, which are connected by the respective flues 4 and 5 with the ports, 6 and 7, communicating with the regenerators 8 and 9, the flues 5, communicating 35 with the chambers 12 and 13, between the regenerator-walls 10 and 11 and the regenerators 8 and 9. The chambers 12 and 13 are provided, respectively, with the sand bottoms 14 and 15, extending downwardly and out- 40 wardly to the doors or manholes 16 and 17 of the closures 18 and 19 therefor. The chambers and passages thus formed, divided by the walls 10, 11, and 20, have their outer walls 21 and the connecting-arches 22 and 22' 45 bound together with the interior walls by the trusses 23 and the tie-rods 24. The hearth 25 is carried by the I-bars 26, resting upon the longitudinal girders 27, which are carried by the walls of the regenerators 9. These girders have their ends engaged by the shoes 28, which, with the I-bars, carry the chill-frames 29, above the regenerator-chambers 9, the

wall 11' of the flue 5 being supported by the shoe and frame.

It will now be understood that slag or other matter overflowing from the furnace-chamber 1 through the ports 3 will descend through the flues 5 to the slag-chambers 14 and 15, whose outwardly-inclined bottoms render it readily removable through the doors 16 and 17 or through the closures 18 and 19.

The gas-ports at each end of the furnace are provided with separate passages to separate slag-chambers, and each of these passages has a separate port communicating with a regenerator. As the passages at each end of the furnace communicate with different parts of the regenerators in passing therethrough the waste gases to the stack and the gas for combustion to the furnace-chamber, a better 65 distribution of the gases is obtained, both in heating the checkers and in heating the incoming gases, for the separate flues connected with the regenerators at different points thereof avoid the concentration of the gases 70 in a single current which does not reach the extremities of the regenerator. In like manner the air-ports at each end of the furnace are provided with separate passages, connected by separate ports with different parts of the 75 regenerator, so that the outgoing waste gases and the incoming air are better distributed and a better heating effect obtained.

Having described my invention, I claim:

1. A furnace having a heating-chamber, a plurality of regenerators at each end of said heating-chamber, a plurality of gas-passages connecting each end of said heating-chamber with different parts of a regenerator therefor, a separate slag-pocket connected with each of said passages and separated from the connections thereof with the regenerator therefor, and a plurality of air-passages connecting each end of said heating-chamber with different parts of a regenerator therefor, substantially as specified.

2. A furnace having a heating-chamber, a plurality of regenerators at each end thereof extending transversely thereto, a plurality of separate passages connected with each end of said heating-chamber and extending downwardly between the regenerators therefor, a slag-pocket at the bottom of each of said passages, and separate ports connecting one of

said regenerators with said passages above
said slag-pockets, said heating-chamber being
supported at its respective ends by walls of
but one of the regenerators connected there-
5 with.

In testimony whereof I have hereunto set
my hand, this 26th day of December, A. D.

1903, in the presence of the subscribing wit-
nesses.

J. A. HERRICK.

In presence of -

JOHN THIEL,
UTLEY E. CRANE, Jr.
